UNITED STATES PATENT OFFICE.

JOHN P. STEPPE, OF NEW YORK, N. Y., ASSIGNOR TO SIGMUND STERNAU
AND LIONEL STRASSBURGER, OF SAME PLACE.

DESIGN FOR A BRUSH-HOLDER.

SPECIFICATION forming part of Design No. 33,702, dated December 11, 1900.

Application filed November 13, 1900. Serial No. 36,414. Term of patent 7 years.

To all whom it may concern:

Be it known that I, JOHN P. STEPPE, a citizen of the United States, residing in the borough of Brooklyn, city of New York, State of New York, have invented and produced a new and original Design for Brush-Holders, of which the following is a specification, reference being had to the accompanying drawings, forming part thereof.

10 My invention relates to a new and original design for holders for tooth and nail brushes and similar articles.

The leading or essential features of my design comprise a plain back plate having its edge ornamented with a series of connected beads and from which extend, essentially, C-shaped projections arranged approximately at right angles to the plane of said plate.

15 My design is illustrated in the accompany-

ing drawings, forming part of this specification, and in which—

Figure 1 is a front view, and Fig. 2 a plan view.

A represents the plate, which is essentially plain, its edge being ornamented with a series of connected beads. Projecting from the plate are a series of essentially C-shaped projections C, which are maintained in a plane at right angles to the plate A.

What I claim is—

20 The design for a brush-holder herein shown and described.

This specification signed and witnessed this 8th day of November, 1900.

30 JNO. P. STEPPE.
